UNITED STATES PATENT OFFICE.

GEORGE R. WELCH, OF DETROIT, MICHIGAN.

CARBURETOR.

Original application filed July 21, 1919, Serial No. 312,304. Divided and this application filed May 5, 1925. Serial No. 28,171.

To all whom it may concern:

Be it known that I, GEORGE R. WELCH, a citizen of the United States, residing at 7337 Third Avenue, Detroit, in the county of Wayne and State of Michigan, have invented certain new and useful Improvements in Carburetors, of which the following is a specification.

The invention relates to a carburetor for use with an internal combustion engine by means of which a low grade fuel can be satisfactorily used. This application is a division of my application Serial No. 312,304, filed July 21, 1919.

It is a primary object of this invention to provide a structure in which the exhaust gases are employed for vaporizing the incoming fuel charges by transmitting heat to the surface over which said charges pass. More specifically, the invention comprehends a device of this character embodying a closed chamber into which the exhaust gases are introduced whereby the pulsating pressure causes a flow of the gases into and out of this chamber.

In the drawings forming a part of this application,

Figure 1 is a side elevation of a portion of an engine with my preferred form of carburetor in place thereon, with the float chamber thereof in vertical section and other parts broken away.

Fig. 2 is a section of the carburetor detached on the line 2—2 of Fig. 1.

Fig. 3 is an enlarged section on the line 3—3 of Fig. 2.

Referring to Fig. 1 of the drawings, 5 is a portion of a four cylinder engine. 6 is the intake manifold and 7 is the exhaust manifold of the engine. In the preferred form, my improved carburetor consists of a depending body casing 8 which is preferably cast integral with the exhaust manifold. The walls decrease in width toward the lower end and are provided with pierced internally threaded lugs 9. At the top, casing 8 is as wide as the distance transversely and horizontally through the manifold and the front edges are faced for the reception of a thin sheet metal plate 10 which forms the inner wall of the narrow air passage 11. An outer plate 12 having flanges which control with the edges of plate 10, and having lugs 13 which register with lugs 9, is secured to casing 8 by screws 14 which pass through

lug 13 and screw into lugs 9. A port 15 in the upper portion of plate 12 admits air to the passage. A float chamber casing 16 has an attaching member 16^a which is recessed slightly at the top to form a continuation of passage 11 and has a vertical channel 18 which opens into passage 11. This attaching member is secured to casing 8 by bolts 8^a which pass through flanges 8^b on the bottom edge of casing 8 and flanges 16^b on member 16^a as shown in Fig. 4. A channel 19 connects with channel 18. A port 20 opens from channel 19 into the float chamber and is controlled by needle valve 22 which regulates the amount of fuel that is allowed to pass through port 20. The float chamber has a cover 23 provided with the boss 24 having a channel 25 therein. A port 26 connects channel 25 with the float chamber. Port 26 is controlled by valve 27 which is operated by lever 28 pivoted to casing. A float 29 is secured to lever 28. A liquid supply pipe 30 is connected to boss 24. Opposite plate 10 is a like thin plate 31 which is covered by a U-shaped plate 32 which is secured to body and forms a narrow full passage 33 which passage opens into a channel 34 in boss 35 on plate 32. A tube 36 is connected to boss 35 and opens into the air inlet casing 37 which has mounted therein the air regulating valve 39, the bottom of which is heavier than the top. Casing 37 is provided with butterfly valve 40 having operating lever 41 which is operated by the usual pull rod, not shown, from the driver's seat. Said casing has attaching lugs 42 for attachment to the intake manifold 6. The space between plates 10 and 31 opens at the top into the exhaust manifold.

The plates 10 and 31 are made of brass from .010" to .025" in thickness and are preferably made of brass of a thickness of .015". By reason of its increased conductivity plates formed of aluminum alloy (e. g. duralumin) may be substituted for the brass and these aluminum alloy plates may have a thickness of .015" to .050".

Operation.—Air enters through the opening 15, flows down 11 and is heated by contact with the thin wall 10 which is in contact with the interior of the exhaust pipe 7. Air flows along the horizontal passage connecting the passage 11 with passage 33, past the fuel nozzle 18 where the heated air picks up fuel issuing therefrom. The

heated air, together with the fuel, passes up the passage 33 where the fuel is vaporized by contact with the thin plate which in its turn is heated by contact with the exhaust 5 gases from the exhaust pipe 7. The wedge shaped passage provided for the vaporized fuel prevents the expansion in volume producing any back pressure. Further, the increase in area of the passage 33 slows down 10 the velocity. Hence the gases will not carry in suspension any unvaporized fuel which is thereupon deposited on the walls of the passage where it flows down by gravity and is vaporized by the heated fresh air entering 15 the bottom of the passage 33. A heated rich mixture therefore issues from the outlet from the passage 33. This rich mixture is diluted with cold air by an automatic diluting valve in the well-known manner 20 and is thereafter taken into the engine where it is burnt.

Cleaning.—In order to clean the vaporizer the plate 31, where carbon accumulates, and the cap screws 14 are removed and the plate 25 31 is freed from the exhaust pocket 8. The plate 31 is then easily removed when it can be cleaned very easily. The carbon is removed from both sides because a certain amount of carbon accumulates on the inside in contact with the exhaust gases. The cost of renewing a plate is only a matter 30 of a few cents. The whole operation of replacing the old plate 31 for a clean new one only takes about five minutes.

35 I claim as my invention:

1. The combination with an internal combustion engine having an exhaust pipe, of a closed chamber communicating with said exhaust pipe by a single opening, so that the pulsating pressure in said exhaust pipe causes a flow of hot gases into and out of said chamber, said chamber extending to a substantial distance from said exhaust pipe, means forming a mixing chamber, said 40 chamber having an air inlet, a fuel nozzle discharging into said mixing chamber, and means forming a passage leading from said mixing chamber to the intake of said internal combustion engine, a wall of said 45 passage being formed by a wall of said closed heating chamber, the parts being so arranged that the air and fuel mixture first

comes into contact with the wall of the heating chamber remote from the exhaust pipe.

2. In combination with an internal combustion engine having an exhaust pipe, a heating device comprising a closed chamber communicating with said exhaust pipe by a single port only, so that the pulsating 60 pressure in the exhaust pipe causes a flow of hot gases into and out of said chamber.

3. The combination with an internal combustion engine having an exhaust conduit, a heating device comprising a closed chamber having a wall of thin metal, means for establishing communication between said exhaust conduit and said chamber, whereby the pulsating pressure of the exhaust conduit causes a flow of hot gases into and out of 70 said chamber, and a fuel passageway disposed adjacent the thin wall of said closed chamber through which fuel passes for delivery to the internal combustion engine.

4. The combination with an internal com- 75 bustion engine having an exhaust pipe, a heating device comprising a closed chamber having tapering side walls communicating with the exhaust pipe at a single port only, so that the pulsating pressure in the 80 exhaust pipe causes a flow of hot gases into and out of said chamber, a casing surrounding said chamber, and means for admitting fuel to said chamber at the small end of a tapered wall thereof to pass over said wall 85 toward the large end.

5. The combination with an internal combustion engine having an exhaust pipe, of a closed chamber communicating with said exhaust pipe having a tapering wall of thin 90 metal, means for establishing communication between the exhaust pipe and said chamber whereby the pulsating pressure of the exhaust conduit causes a flow of hot gases into and out of said chamber, a fuel 95 passageway disposed adjacent the thin wall of said closed chamber, means for introducing fuel to the passageway at the narrow portion of said thin wall to pass over the tapering wall toward the wider portion 100 thereof for delivery to the internal combustion engine.

In testimony whereof I affix my signature.
GEORGE R. WELCH.
